UNITED STATES PATENT OFFICE.

HORACE B. GALE, OF SAN FRANCISCO, CALIFORNIA, ASSIGNOR TO
CHARLES C. WORTHINGTON, OF IRVINGTON, NEW YORK.

VALVE-MOVEMENT FOR PUMPS.

SPECIFICATION forming part of Letters Patent No. 607,845, dated July 26, 1898.

Application filed March 10, 1894. Renewed December 23, 1897. Serial No. 663,261. (No model.)

To all whom it may concern:

Be it known that I, HORACE B. GALE, a citizen of the United States, residing at San Francisco, in the county of San Francisco and State 5 of California, have invented certain new and useful Improvements in Valve-Movements for Pumps; and I do hereby declare the following to be a full, clear, and exact description of the invention, such as will enable others skilled in 10 the art to which it appertains to make and use the same.

The main object of the invention is to provide improved means for quickly seating pump-valves before the reversal of the motion 15 of the propelling mechanism, thereby obviating the shocks caused by the violent seating of the valves in an ordinary crank-and-fly-wheel pump when run at high speed and under heavy pressure. By thus enabling 20 pumps doing any duty, however heavy, to run smoothly and quietly at a high rotative and piston speed a comparatively small pump is able to do the work which would require a much larger and more expensive one equipped 25 with the ordinary valves.

The fundamental principle of my invention is to provide for the application of a definite and sufficient force to the pump-valve to 30 close it quietly just before or at the instant of the reversal of motion of the piston, thereby preventing any backflow or "slip" of the fluid through the port and the accompanying pounding of the valve to its seat, the valve being left free at other times, so that it may 35 oppose as little resistance as possible to opening and to the passage of the fluid. The devices by which I carry out this principle are illustrated by the accompanying drawings, in which—

40 Figure 1 is a sectional diagram exhibiting the elements of my invention disconnected from the remainder of the pump mechanism. Fig. 2 is a vertical sectional elevation, and Fig. 3 a horizontal section, on the line S S of 45 Fig. 2, illustrating the details of construction and arrangement of a set of the valves and the method of attaching them to the cylinder of a horizontal pump of the type distinguished as having a single-acting suction and a double-acting delivery. Fig. 4 shows the invention applied to the suction and delivery valves

of a vertical single-acting plunger-pump, and Fig. 5 is a vertical section and elevation illustrating its application to a double-acting outside plunger-pump.

55

Similar letters of reference indicate corresponding parts in all the views.

The principle of operation of the device may be explained with the aid of the diagram of Fig. 1, in which A indicates a pump-valve 60 arranged so as to be opened in the usual way by the pressure of the fluid underneath it compressing the light spring a. The upper end of the valve-stem g is connected to a flexible diaphragm m, which forms one side 65 of the chamber B. This chamber, which I call the "pressure-chamber," is connected by the passage D with the valve-chest t, containing a supplemental valve C. From the valve-chest t the passage F leads to any convenient source of fluid under pressure—such as a steam-boiler, compressed-air reservoir, head of water, or the like. The passage E leads to the atmosphere or to some body of fluid under lower pressure. The supplemental 70 valve C is operated by some suitable connection with the mechanism of the pump, and according as it is moved to the left or right from its middle position puts the port D, leading to the pressure-chamber, in communication 75 with the passage E or with the passage F. Thus the pressure applied to the diaphragm m and by it to the pump-valve A is varied by the operation of the supplemental valve. In the figure the mechanism is shown 80 in such a position that the chamber B is in communication with the port E, and the pressure on the diaphragm is such as to permit the fluid driven by the pump-piston to lift the valve A from its seat and to flow 85 through the port in the direction of the arrow. Now if the motion of the pump-piston were to be suddenly reversed, the supplemental valve C remaining in the position shown, a momentary reversed flow of fluid 90 downward past the valve A would result before the spring a would have time to close it and the valve would be driven to its seat with a violence depending upon the pressure of the fluid pumped and the rapidity of reversal of 95 the piston's motion. To forestall this action, the supplemental valve C is moved toward 100

the right just previous to the reversal of the motion of the pump-piston, so as to admit the fluid-pressure from passage F through the passage D to the chamber B. This pressure acting on the valve A forces it quietly to its seat against the gradually-diminishing flow of fluid upward through the port, so that when the reverse motion of the piston begins the valve is already closed. Before the time for again opening the pump-valve A arrives the supplemental valve C has moved back, so as to connect the pressure-chamber B with the exhaust-passage E, thus relieving the pressure on the valve A and allowing it to be opened easily by the fluid as soon as the motion of the piston is again reversed.

With this device the speed of the closing movement of the valve A is limited by the rapidity with which the fluid can enter the chamber B, and this can be regulated by a throttle-valve in the passage F or by adjusting the extent of opening of the valve C. The time when the closing movement begins is conditioned upon the time of movement of the supplemental valve C and may be controlled by adjusting the eccentric or other device by which that valve is driven. The force applied to close the valve A depends upon the pressure of the fluid admitted to the pressure-chamber B and the area of the diaphragm or equivalent device upon which the pressure acts, and by using suitable proportions any required force may be obtained. All the elements affecting the closing of the pump-valve are therefore under control, and by adjustments readily made any desired closing movement may be produced.

This device is applicable to both the suction and delivery valves of a pump and may be applied to either one or the other only or to both, as may be preferred. A single supplemental valve is capable of controlling all the valves of a double-acting pump, as is illustrated in Fig. 5; but, if preferred, a number of separate supplemental valves may be used.

I do not confine my claim to any particular type of supplemental valve or mechanism for accomplishing the alternate admission and discharge of the working fluid to and from the pressure-chamber B, because it is apparent that a variety of mechanisms well known in the art are readily adaptable to the purpose.

The diaphragm m is not an essential feature of the invention, and a piston or equivalent device may be substituted for it, or by properly inclosing the back of the pump-valve A the fluid-pressure in the chamber B may be made to act directly on the valve itself.

In Figs. 2 and 3 I have shown the details of a set of valves—suction, delivery, and supplemental—illustrating what I consider in most cases the best mode of constructing them and attaching them to the pump-cylinder; also, in Figs. 4 and 5 two mechanisms for operating the supplemental valve, attached, re-

spectively, to the rotating and the reciprocating parts of the machinery.

Fig. 2 shows a suction-valve A and a delivery-valve A', both controlled by the same supplemental valve C and pressure-chamber B. s indicates the suction-pipe connection, u a passage in communication with the main chamber k of the pump-cylinder, (see Fig. 3,) and h the connection to the delivery-pipe. The latter connects also to the chamber v of the pump-cylinder, which has no valves. The cross-section of the plunger p' is made of about one-half the area of the main plunger p in order to give on the delivery side the effect of a double-acting pump. Both pump-valves have their stems g and g' extended into the pressure-chamber B through cylindrical openings, in which they fit loosely, so as to slide freely in and out when the valves move, and the latter are further guided by the radial plates z, fitting the sides of the port-openings.

I prefer generally to make the valves without closing-springs, as shown, so that they may oppose as little resistance as possible to the flow of the fluid, their lifting movements being limited by elastic buffers x and x'. It is generally most convenient also to employ the fluid which is being pumped as the working fluid for applying the necessary closing force to the pump-valves, and accordingly the admission and exhaust passages F and E are led from the supplemental-valve chamber t respectively to the delivery-pipe h and the suction-pipe s. The passage D, as before, connects the valve-chamber t with the pressure-chamber B. The action of the supplemental valve C in Fig. 2 is the same as in Fig. 1, except that in Fig. 2 this valve is of the rotary instead of the flat slide-valve type. It is actuated by the rocking lever n, which derives its motion in any suitable way from the pump mechanism.

One of the advantages of the construction shown in Figs. 2 and 3 is that by this method the valves and pipe connections are all included in a single cylindrical casing j, and these may be manufactured and fitted up independent of the pumps to which they are to be applied, the same valve-chest being applicable to a great variety of pump-cylinders. The latter have then simply to be provided with a flanged connection q on the side or in some convenient place for bolting on the valve-chest, as shown. The delivery-valve may be lifted out of the casing when the cover i' is removed, and by removing the cover i access may be had to the suction-valve, which may be taken out also after being detached from its stem g.

The operation of the valves shown in Figs. 2 and 3 can be most readily explained by reference to Fig. 4, which has the advantage of showing all the necessary mechanism in one view. The arrangement of the valves in Fig. 4 is substantially as in Fig. 3, the only differ-

ence being that in Fig. 4 the valve-chest is represented as cast in one piece with the pump-cylinder instead of being bolted to it.

Fig. 4 is a vertical sectional elevation of a single-acting pump, whose plunger *p* is driven by means of the crank *w*, the double beam *y*, and the connecting-links *l* and *l'*. The rocking lever *n*, by which the supplemental valve *C* is actuated, is connected by the rod *r* directly to the main crank-pin *o*. The time and extent of the opening of the valve *C* may be adjusted by means of the movable pin and the slot in the lever *n* or by shifting the angular position of the latter on the valve-spindle. Suppose the rotation of the crank to take place in the direction indicated by the arrow, so that the plunger *p* in the position shown is moving downward and forcing the fluid out of the pump-cylinder *k* through the annular passage *u* and the delivery-valve *A'*, the suction-valve *A* being closed. The supplemental valve *C* is in its middle position, covering the port *D*, and as the small plungers formed by the valve-stems *g* and *g'* are not tight-fitting the fluid-pressure in the chamber *B* is now about the same as that in the pump-cylinder *k*. As the plunger *p* approaches the end of its downward stroke the rocking lever *n* is moved downward and the supplemental valve *C* is rotated into a position which puts the port *D* in communication with the port *E*. The fluid in the chamber *B* can now escape into the suction-pipe, and the pressure in chamber *B* is reduced to the suction-pressure, so that the superior pressure on the top of the delivery-valve *A'* forces it to its seat. If the adjustments are properly made, when the plunger *p* begins its upward stroke the delivery-valve *A'* will be closed. The pressure-chamber *B* being then in communication with the suction-pipe, the suction-valve *A* experiences no resistance to opening. As the plunger *p* nears the top of its upstroke the supplemental valve connects the chamber *B* with the delivery-pipe *h*, and the fluid entering the chamber *B* presses on the end of the valve-stem *g* and shuts the suction-valve in the same manner as was explained in connection with Fig. 1. When the next downstroke begins, the suction-valve is therefore already closed, and the pressure in the chamber *B* is equal to that in the delivery-pipe, so that now the delivery-valve *A'* experiences no resistance to opening. Injurious leakage into or out of the chamber *B* around the valve-stems *g* and *g'* can take place only while one of the pump-valves is in the act of closing, because at other times the pressure in the chamber *B* is the same as that in the pump-cylinder. The loss of fluid in operating the valves in this way is believed to be considerably less than the loss from "slip" would be with valves closed in the ordinary way.

Fig. 5 shows how a single supplemental valve *C* may be employed to govern the closing of all the suction and delivery valves of

a double-acting pump and illustrates also a method of deriving the motion of the supplemental valve from the main piston-rod, which is applicable especially to non-rotative pumping machinery. A pair of pump-valves *A* and *A'* and an intermediate pressure-chamber *B*, arranged as in Fig. 2, are connected to each end of the pump-cylinder. An additional port *D'* is made in the supplemental-valve casing, and a separate connecting-passage leads to each pressure-chamber. The action of the valves at each end of the double-acting pump-cylinder is exactly the same as has been explained for the single-acting pump. The rocking lever *n*, which actuates the supplemental valve *C*, is here driven by the rod *r*, which is provided with adjustable tappets *b* and *b'*, engaged by the block *e*, pivoted on the swinging lever *d*, whose lower end is linked to the cross-head *f*.

It being apparent that the form and arrangement of parts in my invention are capable of considerable variation without departing from the principles involved in its operation, I do not confine my claims strictly to the specific forms and arrangements shown and described; but

What I claim as my invention, and desire to secure by Letters Patent, is—

1. The combination, in a valve-movement for pumps, of a casing containing induction and discharge valves and an intermediate pressure-chamber, independent plungers or their equivalents attached to the said valves and entering the intermediate pressure-chamber, passages connecting the intermediate pressure-chamber with the fluid-spaces on, respectively, the induction and discharge side of the induction and discharge valves, and a supplemental valve mechanism controlling the flow of fluid through the said passages, substantially as set forth and for the purposes described.

2. The combination, in a valve-movement for pumps, of a casing communicating with the working cylinder and containing induction and discharge valves and an intermediate pressure-chamber, plungers or pistons formed by extensions of the valve-stems entering said pressure-chamber, and a supplemental valve mechanism actuated by the pump mechanism by which the fluid-pressure in said chamber is varied so as to accelerate the closing of the induction and discharge valves, substantially as set forth and for the purposes described.

3. The combination, in a valve-movement for pumps of a casing containing induction and discharge valves and an intermediate pressure-chamber, plungers or pistons formed by extensions of the valve-stems entering said pressure-chamber, and a supplemental valve mechanism and passages by which the fluid-pressure in said chamber is varied so as to accelerate the closing of said suction and delivery valves, substantially as set forth and for the purposes described.

4. The combination with a pump-valve, of a plunger or piston projecting from its lower or face side, a body of fluid applied to press upon said plunger or piston, supplemental valve mechanism controlling said body of fluid, and means for actuating said supplemental valve mechanism to vary the pressure of said body of fluid upon said plunger or piston, substantially as described.
5. The combination with a pump-valve, of a plunger or piston projecting from its lower or face side, a body of fluid applied to press upon the said plunger or piston, and a supplemental valve mechanism, operated by connection with the pump, whereby the pressure of the said body of fluid is varied so as to accelerate the closing of the said pump-valve, substantially as set forth.
6. The combination, in a valve-movement for pumps, of an induction-valve and a discharge-valve communicating with the pump-cylinder on the same side of the main plunger, a pressure-chamber distinct from the pump-chamber containing a body of fluid which presses upon the said valves in a direction tending to close the induction-valve and to open the discharge-valve, and means of varying the said pressure during the stroke of the pump, so as to accelerate the closing of each of said valves, substantially as set forth.
7. The combination, in a valve-movement for pumps, of an induction-valve and a discharge-valve communicating with the pump-cylinder on the same side of the main plunger, a pressure-chamber distinct from the pump-chamber containing a body of fluid whose pressure is applied to the said valves in such a way as to tend to close the induction-valve and to open the discharge-valve, and a supplemental valve mechanism operated by connection with the pump, whereby the said pressure is varied so as to accelerate the closing of each of said valves, substantially as set forth.
8. The combination with the induction and discharge valves A, A' and intermediate pressure-chamber B, of plungers g, g' acting on said valves A, A' and acted upon by the fluid in the chamber B, and a valve mechanism for alternately admitting and discharging fluid from said pressure-chamber, substantially as set forth and for the purposes described.
9. The combination with the valves A, A' and intermediate pressure-chamber B, of plungers g, g' acting on said valves and acted upon by the fluid in said chamber, passages E, F, a valve-chamber connected with said pressure-chamber and passages E, F, and a valve mechanism for connecting said chamber with the fluid on the suction and discharge sides of the pump-valves alternately, substantially as set forth and for the purposes described.
10. In a double-acting pump, the combination with the plungers p, of induction and discharge valves A, A' and intermediate pressure-chambers B for the respective plungers p, plungers acting on said valves and acted upon by the fluid in said chambers, a valve mechanism controlling the admission and discharge of fluid from each of said pressure-chambers, and passages E, F controlled by said valve mechanism to connect said pressure-chambers with the fluid on the suction and discharge sides of the pump-valves alternately, substantially as set forth and for the purposes described.
- In testimony whereof I affix my signature in presence of two witnesses.
- HORACE B. GALE.
